No. 693,691.

Patented Feb. 18, 1902.

C. R. DOE.

CAR DOOR FASTENER.

(Application filed Jan. 11, 1901.)

(No Model.)

UNITED STATES PATENT OFFICE.

CHARLES R. DOE, OF MOUNT PLEASANT, IOWA.

CAR-DOOR FASTENER.

SPECIFICATION forming part of Letters Patent No. 693,691, dated February 18, 1902.

Application filed January 11, 1901. Serial No. 42,886. (No model.)

To all whom it may concern:

Be it known that I, CHARLES R. DOE, a citizen of the United States, residing at Mount Pleasant, in the county of Henry and State of Iowa, have invented a new and useful Car-Door Fastener, of which the following is a specification.

My invention relates to a novel door fastening or lock for freight-cars, and has for its object the equipment of a car with a simple and effective locking device for the end door and arranged to be controlled from the side of the car and to be removed from possibility of actuation when the side door of the car is closed.

To the accomplishment of this object my invention consists in providing a movable locking member for the end door and actuating means for said member extended to one side of the doorway at the side of the car and provided with a handle normally retained by a pin to hold the locking member in its locked position and designed to be guarded by the side door when the latter is closed in order to prevent the unlocking of the end door until after the side door of the car has been opened by an authorized person.

The invention further consists in the construction and arrangement of parts to be described, illustrated in the accompanying drawings, and succinctly defined in the appended claims.

In said drawings, Figure 1 is a perspective view of a portion of a freight-car equipped with my device, the end door being shown retracted in dotted lines. Fig. 2 is a sectional view through the subject-matter of Fig. 1, showing certain of the parts in elevation. Fig. 3 is a detail elevation, on an enlarged scale, showing the coöperating relation between the handle of the actuator and its pin; and Fig. 4 is a detail perspective view, on a somewhat-enlarged scale, of the locking device proper for the end door.

Referring to the numerals of reference employed to designate corresponding parts in the several views, 1 and 2 indicate portions of the side and end walls of a freight-car, and 3 and 4 the side and end doors suitably mounted, as usual, to slide laterally for the purpose of permitting access to the interior of the car from the side or end thereof. As usual, the

car structure includes vertical beams or door-posts 5 at the end of the car, and the end door is preferably locked to one of them. I therefore provide an angular slotted hasp 6 on the end door 4, arranged for engagement, when the door is closed, with a staple or keeper 7, projecting from one of the posts 5. The hasp 6 constitutes a projection extending from the end door, and in certain of the claims, therefore, I shall define the hasp member 6 as a projection carried by the end door and arranged for engagement with the locking-lever. Immediately above the staple 7 the post 5 is provided with a slot or opening 8 for the accommodation of a locking-lever 9, pivotally mounted upon an adjacent part of the car structure and provided with an angular locking end 10, designed to pass through the staple 7 for the purpose of locking the hasp 6 to a permanent part of the car structure for the purpose of preventing the opening of the end door 4.

10^a indicates a weight hung from the lever 9 and designed to throw said lever automatically to its locked position. Obviously, however, any preferred form of movable locking member might be substituted for the lever 9, the only essential feature of which is its capability of being moved into or out of its locking position for the purpose of effecting the locking or unlocking of the end door.

I have premised that the end-door-locking mechanism is designed for manipulation from the side of the car, and it is therefore necessary to provide mechanism arranged for manipulation at the side of a car and operatively connected with the locking-lever at the end thereof. A simple embodiment of this mechanism comprises an actuator in the form of a rock-shaft 11, journaled in suitable bearings upon the side wall of the car and extending from one of the side door-posts 12 to a point adjacent to the rear end of the locking-lever 9, where it is provided with an angular end or crank 13, having a loose pivotal connection with the adjacent end of the lever. The specific form of this connection is not essential; but the embodiment illustrated in the drawings comprehends the formation of an opening 14 in the locking-lever designed for engagement with the end of the crank 13. At the end of the actuator or rock-shaft 11 opposite the crank 13 is formed an angu-

lar end constituting a handle 15. The handle 15 of the actuator is designed to be swung laterally for the purpose of rocking the rock-shaft 11 to oscillate the crank 13 and swing the locking-lever 9 into its locked or unlocked position, as the case may be. This a groupment of elements—that is to say, the locking element of the end door and the actuator operatively connected with said member and arranged for manipulation only at the side doorway of the car after the side door has been opened—comprehends a complete embodiment of the invention in its broadest aspect; but I prefer to provide individual locking mechanism for the actuator, so that the latter will be retained even after the side door is opened, unless the attendant purposely effects its release. I therefore provide in the side door-posts 12 a pair of recesses or sockets 16 and 17 for the reception of a locking-pin 18, which when in the upper socket 16 projects into the path of movement of the free end of the handle 15 to prevent the swinging of the handle and the unlocking of the end door until after the pin 18 has been removed. This pin is suspended from a flexible piece or chain 18^a, and when withdrawn from the upper socket is inserted in the socket 17, as shown in dotted lines in Fig. 3.

It will now be seen that the side door of the car serves not only to prevent access to the handle of the actuator, but also to the pin provided for the retention of said handle, the equipment of the car with these devices being effected in a manner to prevent interference with the usual manipulation of the main or side doors.

In order that the various elements of the mechanism may be entirely removed from access or observation, they may be inclosed within the walls of the car structure and between the inner and outer sheathings or linings thereof; but by preference the parts are mounted in the positions shown. If desired, a slotted casing or housing 19 may be mounted upon the post 5 to inclose and protect the locking device proper, the slot or opening 20 in said casing being provided to permit the withdrawal of the hasp.

From the foregoing it will appear that I have produced a simple, inexpensive, and highly-efficient fastening for the end doors of freight-cars or the like designed to be controlled by a movable member—as, for instance, a side door located at a distance from the door to which the fastening is applied; but I wish it to be distinctly understood that I do not limit myself to the structural details illustrated and described, nor to the application of my device in any particular connection, since it is obvious that it may be made to serve various purposes other than the protection of freight-cars and may be organized and arranged in a variety of ways without departing from the spirit of the invention. I therefore reserve the right to effect such changes, modifications, and variations of the construc-

tion and mode of application herein described as may be clearly embraced within the spirit of the invention.

What I claim is—

1. The combination with a car having side and end doors, of a locking device for one door, an actuator for said locking device disposed out of operative relation with the side door, but exposed for actuation at the side doorway, connections extending along the side and end of the car structure and operatively connecting the actuator with the locking device, and a retaining device for the actuator carried by a fixed part of the car structure and accessible through the side doorway when the side door is in the open position. 70
2. The combination with a car having side and end doors, of a locking device for one of said doors, an actuator for the locking device and provided with a handle disposed out of operative relation with the other door, but exposed for actuation at the other doorway, and a retaining device carried by a fixed part of the car structure and operatively related to the handle of the actuator. 85
3. The combination with a car provided with side and end doors, of a hasp member carried by one door, a locking member mounted in the adjacent wall of the car, an actuator located upon another wall of the car and extending between the other doorway and the locking member, and retaining means for said actuator, said retaining means being independent of the other door but disposed to have access thereto controlled by said door. 95
4. The combination with a car provided with side and end doors, of a hasp member carried by the end door, a keeper disposed for engagement with the hasp member, a locking-lever supported by the car structure for engagement with the hasp member and keeper, and a rock-shaft operatively connected to the locking-lever and provided with a handle disposed adjacent to the side door. 105
5. The combination with a car having side and end doors and door-posts, of a locking-lever arranged to lock the end door, a rock-shaft provided with a crank at one end having connection with the locking-lever and provided at its opposite end with a handle located at the side door-post, and a retaining device carried by said post and disposed in the path of movement of the handle. 115
6. The combination with a car having side and end doors and door-posts, of a locking-lever arranged to lock the end door, a rock-shaft provided with a crank connected to the locking-lever, and with a handle exposed at the side doorway of the car, and a pin removably mounted in one of the side door-posts and serving as a retaining device for the handle. 125
7. The combination with a car provided with side and end doors, of a projection carried by the end door, a locking-lever supported upon the end wall of the car structure for engagement with the projection, a rock-shaft 130

extending along one side of the car and operatively connected with the locking-lever, and a handle on said rock-shaft exposed for actuation at the side doorway of the car.

5 8. The combination with a car having side and end doors, of a locking device for the end door and an actuator for said device, said actuator being out of operative relation with the side door, but exposed for actuation at the side doorway, and connecting devices extending along the side and end of the car and operatively connecting the locking device and actuator.

9. The combination with a car having side

and end doors, of a locking-lever disposed to engage and retain the end door, reactive means for moving the locking-lever to its engaging position, and an actuator operatively connected to the locking-lever and exposed for actuation at the side doorway but out of operative relation with the side door.

In testimony that I claim the foregoing as my own I have hereto affixed my signature in the presence of two witnesses.

CHARLES R. DOE.
